UNITED STATES PATENT OFFICE.

GEORGE B. THOMAS, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ELECTRIC-LAMP SOCKET.

1,206,617.

Specification of Letters Patent. Patented Nov. 28, 1916.

Application filed June 27, 1914. Serial No. 847,700.

To all whom it may concern:

Be it known that I, GEORGE B. THOMAS, a citizen of the United States of America, and residing at Bridgeport, in the county of 5 Fairfield and State of Connecticut, have invented a certain new and useful Improvement in Electric-Lamp Sockets, of which the following is a specification.

My invention relates to electric lamp 10 sockets and particularly to sockets adapted to contain lamps of large candle power, the particular object of my invention being to provide improved means for securing the insulating body of the socket within its 15 casing.

In the accompanying drawings, Figure 1 is a broken elevation of my socket in which my invention is embodied in one form; Fig. 2 is a plan of the insulating body of the 20 socket; Fig. 3 is a plan of the cap portion of the casing; and Fig. 4 is a side elevation of the cap.

In sockets of the present character, the customary method of installation consists in 25 screwing the nipple of the cap onto the supporting wire conduit, fastening the wires to the binding screws on the insulating body of the socket, pushing the latter up within the cap in register with short lugs carried 30 by the cap and taking into shallow recesses in the porcelain body whereupon the socket body is fastened in the cap and in engagement with the lugs mentioned by means of a set screw passing through a peripheral 35 flange or skirt at the lower edge of the cap. The cap and insulating body being thus secured in position, the lower portion or shell of the casing is then passed up over the body of the socket and screwed into the 40 threaded portion of the cap flange, after which the shell is prevented from backing off by means of a set screw.

It has been found in practice that the use 45 of a set screw to hold the insulating body of the socket up within the cap is unsatisfactory, since the pressure of the screw throws the body out of alinement with the axis of the socket and maintains it in this crooked position even after the shell has 50 been screwed into the cap. Consequently when the lamp is screwed into the socket, it emphasizes this crooked position of the socket body, since the lamp projects at a more or less marked angle to the axis of the 55 casing. The present invention obviates this

difficulty. In the form here shown, the socket casing comprises the cap 10 carrying at its upper portion the usual threaded bushing 11, with set screw 12, which bears against the wire conduit and prevents the 60 cap from accidentally becoming loose after it has been screwed into position. A peripheral flange 13 at the lower edge of the cap is internally threaded to engage the threaded upper portion of the shell 14 with- 65 in which the insulating lining 15 is ad- justed as usual. Within this casing is ar- ranged the insulating body 16 of the recep- tacle carrying the usual lamp terminals, of which only the screw shell 17 is here shown. 70 The current is led to the lamp terminals as usual from binding screws 18, of which only one is here shown. A long pin 19 pro- jecting below the lower edge of the cap is 75 rigidly secured thereto at a point within the area of the insulating socket body 16 and in the adjusted position of the latter enters the recess 20 formed at one edge thereof. The flange 21 at the upper edge of the insulating body 16 overlies the inturned upper edge 80 22 of the shell and is clamped between the latter and the shoulder 23 of the cap when the shell is screwed up into position. A set screw 24, carried by the peripheral flange 13 of the cap, engages the upper threaded 85 portion of the shell and prevents the latter from backing off after it has been screwed into position.

The manner of assembling the parts is 90 readily understood. The cap is as usual screwed onto the pipe conduit which enters the threaded nipple 11 and the set screw 12 is then tightened. After the wires have been secured to the wire terminals 18 on the body of the socket, the shell 14 is passed 95 up over the body 16 of the socket until the flange 21 on the latter rests upon the in- turned upper edge 22 of the shell. Inasmuch as the pin 19 projects below the lower edge of the cap flange 13, it readily posi- 100 tioned in the recess 20 in the socket body and the latter is thus held against swiveling while the shell 14 is screwed home within the cap flange 13. The pin 19 serves the second function of properly locating the 105 body 16 of the socket within the cap so that the customary wings cut from the cap lining 25 enter the recesses for the binding screws 18 and overlie the latter. When the shell has been turned home and the flange 21 110

clamped beneath the shoulder 23 of the cap, the set screw 24 is then tightened to hold the cap and shell in fixed position.

I do not limit my invention to the precise construction shown, but claim as my invention:—

1. In an incandescent lamp socket, a casing comprising a shell and a cap having a screw-threaded sleeving connection, an insulating socket body within said casing and having a recess, together with a pin projecting below the lower edge of said cap and adapted to enter said recess in the socket body to prevent the latter from turning with relation to the cap during the assembly of the shell and cap.
2. In an incandescent lamp socket, a casing comprising a shell and a cap having a screw-threaded sleeving connection, an insulating socket body within said casing adapted to be carried by the shell during the assembly of the shell and cap, and means carried by the cap and engaging the socket body in advance of the sleeving of the shell and cap and serving to prevent the rotation of said socket body with relation to the cap during said assembly of cap and shell.
3. An incandescent lamp socket having a casing comprising a shell and cap detachably connected together in sleeved relation-

ship, an insulating socket body within said casing and having lateral recesses for wire terminals and an auxiliary recess, an insulating lining in the cap having ears extending 35 into said wire terminal recesses in the assembled condition of the casing, and means carried by the cap and engaging said auxiliary recess in advance of the sleeving of the shell and cap on the assembly of the 40 latter, for the purpose described.

4. An incandescent lamp socket, having a casing comprising a shell and cap detachably connected together, an insulating socket body within said casing and having lateral 45 recesses for binding-screw terminals and an auxiliary recess, an insulating lining in said cap having portions entering the wire terminal recesses in the assembled position of the parts together with a pin projecting 50 below the lower edge of said cap and adapted to enter said auxiliary recess to properly locate the socket body with relation to the cap and its lining, substantially as described.

In testimony whereof I have signed my 55 name to this specification, in the presence of two subscribing witnesses.

GEORGE B. THOMAS.
